UNITED STATES PATENT OFFICE.

JOHN W. STOLKRANTZ, OF BUFFALO, NEW YORK.

GRAPPLE.

No. 834,590.

Specification of Letters Patent.

Patented Oct. 30, 1906.

Application filed June 27, 1906. Serial No. 323,566.

To all whom it may concern:

Be it known that I, JOHN W. STOLKRANTZ, a citizen of the United States, residing at Buffalo, in the county of Erie and State of New York, have invented a new and useful Improvement in Grapples, of which the following is a specification.

This invention relates to a grapple which is more particularly designed for use in hoisting bundles of bar-iron or rails, but which may also be used for holding other articles of this character while hoisting and transferring the same from one place to another.

The object of this invention is to produce a grapple of this character whereby bundles of bars or the like may be easily and expeditiously transferred from one place to another without liability of accidents and with the least expenditure of manual labor.

In the accompanying drawings, consisting of two sheets, Figure 1 is a side elevation of my improved grapple, showing the same applied to a bundle of railway iron and suspended from a hoisting-tackle. Fig. 2 is a fragmentary sectional view of the shackle or upper holder applied to the upper end of the bundle. Fig. 3 is a longitudinal section of the bucket or lower holder which receives the lower end of the bundle. Fig. 4 is a transverse section of the bucket. Fig. 5 is a perspective view of the grapple, showing the position of the parts ready to be applied to a bundle of bars or rods.

Similar letters of reference indicate corresponding parts throughout the several views.

The bucket or lower holder forming part of my improved grapple has a hollow body A, which is of rectangular form in cross-section and open at its front end, while its rear end or bottom a is inclined and provided on its outer side, with one or more handles b, which are grasped by the attendants in applying the bucket to or removing the same from the load. The bucket is pivotally supported by two supporting-cables C, which latter are arranged with their lower ends on opposite sides of the bucket-body and provided with eyes or loops c, which receive pivot-pins D on the outer side of the side walls d of the bucket-body. These pivots are arranged on the central parts of these side walls, so that the bucket when empty is balanced and assumes a substantially horizontal position by gravity with its open end facing laterally, as shown in full lines in Fig. 3, in which position the bucket can be easily

pushed over the end of a bundle of bar-iron A', which is arranged horizontally, as shown by dotted lines in Fig. 3. If the bucket were not thus balanced on the supporting-cables, it would be difficult to turn the same into the position which it must assume for engaging the end of the bundle of bar-iron, owing to the weight of the bucket.

In order to prevent the bottom or back of the bucket-body from becoming worn unduly, a buffer or block E of wood or similar material is arranged on the inner side of its back. This buffer receives the wear of the bundle of rails, which rest at their ends 60 against the same and can be readily renewed, thus preserving the serviceability of the bucket.

On opposite sides of the bucket-body are arranged guard walls or plates F, which are connected at their lower and rear ends by transverse webs f f' with the adjacent lower and rear parts of the bucket-body, while their upper and front edges are disconnected from the adjacent parts of the bucket-body 65 and preferably curved or rounded, as shown in Figs. 1 and 5. These guard-plates form pockets on opposite sides of the bucket-body, which receive the lower ends of the supporting-cables and serve to protect the same and 70 avoid interference of the same with obstructions while the grapple is transferring the load. Each of the pivots which receives the lower end of one of the supporting-cables is secured at its inner end to one side wall of 75 the bucket-body and at its outer end to the adjacent guard-plate, whereby the same is firmly supported and the grapple is not liable to give way while in use. By curving the upper and front edges of the guard-plates 80 the same are not liable to interfere with the supporting-cables while turning the bucket-body relatively thereto.

g' represent rollers pivoted transversely at the front and rear ends of the bucket-body 85 on the lower side thereof. When the bucket is loaded, its open front end faces upwardly. Upon lowering the loaded bucket upon the place where the load is to be deposited the rear roller g' strikes the floor first, and as the 90 lowering of the bundle continues the bucket rolls laterally on the rear roller until it assumes a horizontal position, together with the bundle, and its front roller g also rests on the floor. The bucket-body may now be withdrawn horizontally from the bundle of bar-iron, which movement is facilitated by reason 95

2
of the rolling support on the floor provided at the front and rear ends of the bucket.

The shackle or upper holder forming part

5 of my improved grapple is applied to the upper end of the bundle of bar-iron which is to be shifted and consists, essentially, of a transverse yoke H, of substantially U shape, applied to the upper side of the bundle, and a flexible tie I, such as a chain or cable, applied

10 to the under side of the bundle and connected at its opposite ends with opposite ends of the yoke. On the lower side of its central part the yoke is provided with two lugs or ears h h', which are connected by clevises or pivoted loops j with the upper ends of the supporting-cables, and on its upper side this part of the yoke is provided with a lug or ear h', which is attached by a clevis k with a hanger k', which receives the hook l of the hoisting-

15 tackle L. One end of the tie or chain I is preferably attached permanently to the companion end of the yoke, while its opposite end is provided with a large link i, which detachably engages with a hook m on the opposite 20 end of the yoke. In order to avoid accidental disengagement of the link from the hook while carrying a load, a keeper n is provided, which is pivoted on the adjacent part of the yoke by means of a pin o, so that its 25 free end can swing into and out of the mouth of the hook, and thus either confine the link in the mouth of the hook or permit its removal therefrom. The keeper is held in its operative position, in which it closes the 30 mouth of the hook, by means of a locking-pin p, passing through coinciding openings in the keeper and the yoke.

In applying my improved grapple to a bundle of bar-iron or similar material the bucket 35 is first pushed with the open end of its body horizontally over one end of the bundle and then the yoke of the shackle is placed over the opposite end of the bundle and coupled therewith by passing the chain I underneath 40 the bundle and securing its link in the hook of the yoke. Upon now raising the shackle by means of the hoisting-tackle the bundle carried by the grapple assumes a substantially vertical position, as shown in Fig. 1. 45 The bundle is carried in this position to the unloading-place. Upon lowering the grapple

55 the bucket strikes the floor first and then rolls laterally under the weight of the load until the upper end of the bundle has also been lowered upon the floor. The chain and yoke are now detached from the upper end of the bundle and the bucket removed from the lower rear end thereof ready for receiving another load.

60 I claim as my invention—

1. A grapple comprising a hollow body, guard-plates arranged at the sides of the body, supporting-cables having their lower ends arranged in the spaces between the sides of the body and said guard-plates, and 65 pivot-pins which receive said cables and each of which is supported at its inner end on one side of the body and at its outer end on the adjacent guard-plate, substantially as set forth.

2. A grapple comprising a hollow body, guard-plates arranged at the sides of the body and each connected at its lower and rear edges by transverse webs with the lower and rear parts of the body and having its upper and front edges curved, supporting-cables having their lower ends arranged in the spaces between the sides of the body and said guard-plates and provided with eyes, and pivot-pins which receive said eyes and 70 each of which is secured at its inner end on one side of the body and at its outer end on the adjacent guard-plate, substantially as set forth.

3. A grapple comprising a U-shaped yoke 75 adapted to engage with one side of the load, a flexible tie adapted to engage with the under side of the load and permanently connected at one end with one end of the yoke, and means for detachably connecting the 80 other end of the tie with the opposite end of the yoke, consisting of a link arranged on the tie, a hook arranged on the yoke and receiving said link, and a keeper pivoted on the yoke and movable into and out of the mouth 85 of said hook, substantially as set forth.

90 Witness my hand this 15th day of June, 1906.

JOHN W. STOLKRANTZ.
